UNITED STATES PATENT OFFICE

JOHN FOLINO, OF WILKINSBURG, PENNSYLVANIA, ASSIGNOR OF ONE-FOURTH TO
WILLIAM B. JASPERT, OF MOUNT LEBANON, PENNSYLVANIA

AEROPLANE

Application filed March 13, 1931. Serial No. 522,330.

This invention relates to a mechanical pilot for automatically controlling aeroplanes in their flight, and it is among the objects thereof to provide apparatus which shall be adapted to automatically maintain an aeroplane in a predetermined course of straight flight, which shall be adapted to automatically correct any change or variation affecting the horizontal stability and equilibrium of the plane and which shall be adapted to act to maintain the plane substantially at uniform height above sea level.

A further object of the invention is the provision of simple and durable mechanical means, electrically operated, to control the rudder, elevator and ailerons of an aeroplane in response to automatic control switches and other control devices which, although instantly responsive to variations or deviations from the course of flight, shall not be so sensitive as to render the control operative when the plane is subjected to undue vibration or air bumps.

It is a primary object of the invention to provide a novel form of tilting switch which is especially designed to control the elevator and aileron operating mechanism.

A further object of the invention is to provide means for rendering the automatic elevator control means inoperative when the aeroplane is under control of the automatic altitude regulating means.

It is a still further object of the invention to provide apparatus of the above designated character which shall be of simple and durable mechanical construction, which shall be reliable and dependable for use for which it is intended, and which shall be of minimum weight and of compact form so that it may be located in a portion of the plane where it will be out of the way.

These and other objects of the invention will become more apparent from a consideration of the accompanying drawings in which like reference characters designate like parts and in which

Figure 1 is a top plan view partially in section of a mechanical control mechanism for aeroplanes embodying the principles of this invention;

Figures 2 and 3 are end and side elevational views, respectively, of the device shown in Figure 1:

Figure 4 a longitudinal cross-sectional view of a special type of control switch:

Figure 5 a cross sectional view of the switch taken along the lines V—V, Figure 4:

Figure 6 a cross sectional view of a plunger employed in the mechanism of Figure 7, illustrating the cable connection therewith:

Figure 7 a wiring diagram of the electrical connections of the various control elements: and

Figure 8 a view in perspective of an altitude rectifier which is employed in a manner to be herein set forth.

Before describing the invention in detail, it is well to consider the characteristics of the modern aeroplane and the means commonly employed for controlling it in flight. The plane is supported in flight by the air pressure produced under the wings of the plane, and even with the high degree of stability claimed by plane designers, it is well known that a plane in flight is subjected more or less to inclinations and deviations which must be promptly corrected to maintain equilibrium, stability and direction of flight.

As now generally practiced, such inclinations and deviations are corrected by the pilot by manually operable means, namely, the joy stick and pedals, and there are six correcting actions required to maintain stability and direction; two controlling the ailerons or the rolling axis of the plane; two controlling the elevational or pitch axis; and two controlling the rudder for direction; and by properly manipulating the joy stick and pedals, the control elements are moved exactly as required. The corresponding actions are effected through mechanical linkage or gearing having cable connections with the operating shafts of the joy stick and pedals; all of which being essentially in tension when acting upon the respective devices, whereby two cables are required to operate each control for the exertion of opposed controlling forces.

In accordance with the present invention, the control is automatically effected through

mechanism, the character of which will become apparent from a detailed description of the structure disclosed in the accompanying drawings.

- 5 With reference to Figures 1 to 5 inclusive of the drawings, the numerals 1-1', 2-2', 3-3', designate groups of magnetic coils or solenoids which are secured to an iron frame 4 which constitutes a common magnetic iron 10 core for all of the solenoid windings. The solenoids are maintained in proper alinement by tubes 6 preferably constructed of aluminum to minimize their weight and which are secured to the frame 4 by screws 5. Two solenoids constituting a group, are arranged in coaxial alinement and are adapted to act upon movable plungers 7 disposed for axial movement in tubes 6 in which they are normally biased in the direction of the solenoids 15 by coil springs 8. Springs 8 are adapted to abut against end rings 9 secured in the ends of the aluminum tubes 6, as shown in cross section in Figure 1.

Each solenoid acts upon its own individual 20 plunger and each pair of plungers are joined by a cable 10 in the form of a loop which is disposed around sheave wheels 11 and fastened at its loose ends to the plungers 7 in the manner shown in Figure 6 of the drawings.

25 The ends of the cable loop are secured by clamping jaws 12 which fit into a hollow screw plug 13 having an external thread 14 which interacts with the thread 15 provided centrally in the plunger 7. A hollow screw 30 16 and a cap screw 17 secure the clamping members 12 in the plug 13 so that when the ends of the cable 10 are thus secured they cannot be pulled out of their connections with the plungers 7.

35 Referring to Figures 2 and 3 of the drawings, the looped cable 10 passing over the sheave wheels 11 are connected to a control cable 18 by means of clamps 19, the control cable 18 being movable with the cable loops 40 10 in response to varying actions of the magnetically actuated plungers 7. The control cable 18 has its free ends 20 and 21 connected to the control surfaces of the aeroplane, such as the rudder, elevator, or ailerons and the 45 degree of movement of the control cable is dependent upon the length of stroke or the movement of the plungers 7.

50 As shown in Figures 1 and 2, there are three groups of solenoid actuated plungers 55 each of which constitutes a control in two directions for the cables, thus the groups operated by solenoids 1-1', may be connected by the control cable ends 20-21 to the rudder, the groups 2-2' by their connection to control cable ends 22-23 to the elevator; the group 3-3' by their control cable ends 24-25 to the ailerons. The frame 4 of the device may be mounted on uprights 26 of the pilot's chair by means of cross bars 4' which 60 65 are clamped thereto by screws 27.

To provide for suitable adjustment of the stroke of the plungers 7, the sheave wheel spindles 28 and 29 on which wheels 11 are mounted, are secured at their ends in brackets 30 having elongated slots 31, Figure 3, in which they are freely movable in a horizontal direction. The spindles 28 and 29 are provided with end collars 32 to hold them in frame 4' and spacing collars 34 are provided for axially spacing the sheave wheels or cable pulleys 11 which are free to rotate independently of the rotary movement of the spindles. 70

75 Spindles 28 and 29 are normally biased towards each other by the coil springs 8 within the tubes 6 and adjustable abutments are provided against which the shafts are held by the springs. The abutments consist of slotted sleeves 36 having screw threaded ends 37 disposed in threads of the slots 31 of brackets 30. The adjustable screw 37 varies the spacing of the abutments to vary the center distance of the spindles 28 and 29 and the screw mechanism in turn is operated through a crank 38 which is connected through a worm gear and worm screw 39 and 40, respectively, with the adjusting screws, they being all rendered adjustable simultaneously by operation of the hand crank 38. 80

85 By turning the hand crank 38, the spindles 28 and 29 may be contracted or expanded with respect to the solenoids, thereby moving the pulleys towards or away from the coils; the springs 8 act upon plungers 7 to at all times hold the sheave wheel spindles 90 against the movable abutments 36 of the adjusting screw mechanism. By means of this adjustment, provision may be made to adapt the mechanism to different sized planes and to vary the stroke of the plungers as desired. 95

100 In Figure 1, a plurality of mercury switches 41 and 42 are shown with their longitudinal axes disposed at right angles to each other and coincident with the longitudinal and transverse axes of the aeroplane in which they are mounted. Although the switches are shown in Figure 1 as mounted adjacent the control mechanism, they may be mounted in any suitable portion of the fuselage or wing structure such as the dashboard, for example. The switches are of the type illustrated in Figures 4 and 5 of drawings and consist of a housing 43 of any suitable insulating material such as glass having its ends diverging at one side of its longitudinal center line, the center of the housing being mounted with the apex 44 extending upwardly in the manner shown in Figure 4, this being the normal and operating position of the switch. The switch housing 105 is filled with mercury 45 to the extent that a bubble 46 is produced which normally rests in the apex of the housing as shown. The housing or switch chamber is preferably exhausted and the chamber filled with an insulating inert non-oxidizing gas or liquid to 110

prevent oxidization of the mercury. Terminals 47 and 48 are provided in the ends of the switch, the terminal ends projecting into the mercury as shown and a terminal 49 is 5 provided in one end of the switch with its end projecting into the mercury a substantial distance to assure an efficient electric connection with the mercury at all times. Terminals 47, 48 and 49 are suitably embedded 10 and sealed in the ends of the switch to prevent the escape of the mercury, and are connected to electrical conductors in a power circuit in a manner to be hereinafter described in connection with Figure 7 of the 15 drawings.

The switches are designed to operate in conjunction with a series of relays which are of the normally closed type so that when the bubble 46 of the switch opens the electrical circuit of either of the terminals 47 or 48, the corresponding relay will be open circuited to release its armature which is a movable switch arm designed to close an electric circuit to produce energization of one of 20 the solenoids shown in Figure 1 of the drawings. The switch may be of any suitable cross sectional area, as for example the cylindrical cross section shown in Figure 5 of the drawings, and by means of its angular housing construction, the bubble 46 is supported by the head pressure of the mercury which is equal to the volume of displacement from the apex of the housing to the upper terminals 47 and 48, and it is so constructed to 25 prevent the bubble 46 from responding to vibrations, air-bumps, or slight variations of the plane.

With reference to Figure 7 of the drawings, the solenoids and switches are shown 30 connected in an electrical circuit energized by a generator 50 and these elements are further illustrated as associated with other control mechanism as follows: Solenoids 1-1' are connected by their terminals 51 and 52 to a power line 53 leading to the generator and at their terminals 54 and 56 to normally open contacts 56 and 57 of relays 58 and 59, respectively, which when de-energized, actuate 35 movable armatures 60 and 61 which are biased by springs 62 to make contact with the terminals 56 and 57 to energize the solenoids 1 and 1'.

Solenoids 2-2' are connected at one side by a conductor 63 to the power line 53 and 40 through their other terminals 64-65 to relays 66 and 67 respectively. Similarly, solenoids 3 and 3' are connected through conductor 68 to the power line and by their terminal connections 69 and 70 to relays 71 and 72, respectively. Relays 67 and 66 and 71 and 72 are 45 connected to the mercury switches 41 and 42 to be responsive to their tilting action as explained in connection with Figure 4 of the drawings.

An earth inductor 74 is connected to the

grid element 75 of a pair of electron tube generators 75a and 75b, the plates 76 of which are connected to the relays 58 and 59. The filaments 77 are connected through a conductor 78 to a segment 90 of a control switch. The elevator controlling solenoids 2-2' are further controlled by relays 80 and 81 in response to an altitude rectifier generally designated at 82, Figure 8, of which the arm 83 constitutes the movable arm 83 of the wiring diagram which is adapted to contact terminals 84 and 85 of the relays 80 and 81, respectively. The movable arm 83 is at all times electrically connected with a solenoid 86 which when energized breaks the circuit 50 of the conductor 87 by moving its armature 88 out of contact therewith.

The electrical connection to the positive terminal of the generator 50 is effected through the segment switch by means of a movable 55 arm 89 and contact segments 90, 91 and 92, which segments are of different lengths to permit energizing some of the circuits preliminary to establishing electrical contact with all three control segments.

The operation of the device is briefly as follows: When the plane has taken off and reaches the desired altitude, the arm 89 is moved to contact with the segment 90, thereby energizing filaments 77 of the electron 60 tube generator to preheat them before making contact with segment 91 and through segment 91 the normally closed relays 58-59, 66-67, and 71-72 are energized before the normally open relays 80 and 81 which latter 65 are energized when the arm 89 passes to the short segment 92.

Once the automatic control mechanism is placed in operation, any deviation of the plane or any unstabilizing effects are 70 responded to and corrected as follows: If the nose of the plane suddenly drops, the bubble 46 of the switch 41 will open circuit the terminals 47, thus breaking the circuit of relay 67 which releases its armature and establishes the electrical circuit of solenoid 2' which as previously explained controls the elevators through its plunger by causing movement of the end 23 of the control cable and when the nose of the plane has been 75 righted, the bubble 46 will return to its center position, thus reestablishing the circuit to energize relay 67 and withdraw the armature to open circuit and deenergize solenoid 2'.

Similarly, if the plane would suddenly 80 lurch backwards, the bubble 46 would move forward and open circuit terminal 48 de-energizing relay 66 causing solenoid 2 to be energized which through its plunger pulls the end 22 of the control cable in the opposite 85 direction to operate the elevators to right the plane. Similarly, if the plane tilts sidewise in either direction, the respective end terminals of switch 42 are open circuited whereby solenoid 3 or 3' is energized to operate the 90

ailerons which immediately stabilize the plane.

The altitude of the plane is maintained in response to the altitude rectifier 82 which controls the elevator operating solenoids 2-2' through relays 80 and 81, the relay 86 functioning to prevent the simultaneous oppositional functioning of the electrical control switch 41.

The altitude rectifier 82 operates as follows. When the plane has reached the altitude desired for the course of flight, its valve is opened to equalize the air pressure inside and outside of the expansion box 82' and while the air pressure is thus equalized, the indicator arm 83 will be in neutral position in which position it is inoperatively disposed out of contact with members 84 and 85. If a previous nose dive corrected through the electric switch 41 has resulted in the loss of some altitude, the effect of the loss in altitude will increase the outside air pressure causing contraction of the expansion box 82' and such contraction will operate lever 83 to engage contact 84 which in turn causes relay 80 to be energized to close the power circuit leading to solenoid 2' and to thereby operate the elevator. Simultaneously, with the closing of the contact 84, solenoid 86 is energized to open the circuit 87 of the relays controlled by the electric switch 41 so as to prevent any counter action or interference of the switch 41 with the altitude rectifier. In a similar manner, if the aeroplane has reached a higher altitude, the expansion box 82' will expand due to the difference in the internal and external air pressure and arm 83 will move into contact with the terminal 85, thus energizing the solenoid 81 and establishing the circuit with solenoid 2 to operate the elevator, resulting in the plane gliding to a lower altitude, and simultaneously the relay 86 is energized to prevent interference by the electric switch 41.

The automatic steering of the plane is effected through the earth inductor 74 as follows: The relays 58 and 59 are energized by the electrical energy of the electron tubes and hold their respective armatures 60 and 61 in normally closed position in which position the rudder solenoids 1-1' are deenergized. The rudder maintains its position regardless of how the stability of the plane may be affected, and the earth inductor is also maintained neutral by its internal electro-motive forces which are completely balanced and no current flows in its external circuit which is the grid circuit 75 of the electrode tubes 75a and 75b. When the plane deviates from a straight course, the change in direction will result in a change of the relative position of the brushes of the earth inductor with the earth magnetic field, thereby setting up current in its external circuit. This current will be negative at one of its terminals and

positive at the other, depending upon which direction the plane has deviated from the straight course. When a negative charge is imparted to the grid of the electron tubes, a substantial decrease of the internal electronic flow will take place between the filament and plate, thus deenergizing the relays 58 and 59 as the case may be, to such extent that it releases its armature to temporarily energize the rudder control solenoids 1 or 1' thereby instantly exerting a pull on the rudder to restore the plane to its former direction. When this is accomplished, the normal flow in the electron tube and associated relay will be re-activated by the earth inductor, returned to its former neutral position with resultant deenergizing of the rudder controlling solenoid.

It is evident from the foregoing description of this invention that the electric control system for mechanically and automatically piloting a plane provides for the correction of all deviations from the straight course and provides for stabilizing the plane in response to any deviations, except vibrations or other minor operating characteristics of the plane which would render the apparatus useless.

It is apparent that the automatic pilot mechanism may be employed in conjunction with the standard form of control by connecting the control cable to the operating shafts of the joy stick and foot pedals without in any manner interfering with standard control equipment and without making any provisions for such joint control in the design or construction of the aeroplane.

Although the invention has been illustrated as embodied in a particular form of structure and arrangement of parts, it will be obvious to those skilled in the art that various modifications may be made without departing from the principles herein set forth.

I claim:

1. In an aeroplane, the combination with controls for stabilizing its pitching axis, of electromagnets for actuating said controls, means separate from said stabilizing means for controlling the altitude of the aeroplane, an electrical circuit for said stabilizing and altitude control means, and means for rendering said stabilizing means inoperative when said altitude control means is operating.

2. In an aeroplane, the combination with controls for stabilizing its pitching axis, of electromagnets for actuating said controls, means separate from said stabilizing means for controlling the altitude of the aeroplane, an electrical circuit for said stabilizing and altitude control means, means in said circuit responsive to the pitching of the plane for energizing said electromagnets, means in said circuit for energizing said altitude controlling means, and means for rendering said

- stabilizing means inoperative when said altitude control means is operating.
3. In an aeroplane, automatic control mechanism comprising an iron frame, a plurality of electromagnets mounted on said frame, a plurality of movable armatures adapted to be actuated by said electromagnets, a pair of shafts in spaced relation with said frame, sheave wheels mounted on said shafts, control cables passing around said wheels and secured to said armatures, and means for adjusting the spacing of said shafts with said magnets to vary the distance of movement of said armatures.
- 15 4. In an aeroplane, automatic control mechanism comprising an iron frame, a plurality of hollow electromagnet coils mounted in pairs on said frame, each pair being in coaxial alinement, plungers movable in said coils, the plungers of each pair of coils being joined by a cable looped around a pair of pulleys and control cables fastened to said plunger connecting loops.
5. In an aeroplane, automatic control mechanism comprising an iron frame, a plurality of hollow electromagnet coils mounted in pairs on said frame, each pair being in coaxial alinement, plungers movable in said coils, the plungers of each pair of coils being joined by a cable looped around a pair of pulleys, control cables fastened to said plunger connecting loops, and means for simultaneously separating or contracting said pulleys to vary the stroke of said plungers.
- 35 6. In an aeroplane, automatic control mechanism comprising a frame constituting an iron core for a plurality of electromagnet coils, a plurality of hollow coils mounted in pairs in coaxial alinement on said frame, a movable plunger disposed in each of said coils, a pair of shafts having their axes disposed transversely to the axes of said plungers, sheave wheels mounted on said shafts, cable loops connecting each pair of cooperating plungers and passing around said sheave wheels, means for simultaneously adjusting both of said shafts to vary the length of the cable loops and the stroke of said plungers, and control cables connected to said loops.
7. In an aeroplane, the combination with elevator controls and aileron controls of automatic means for actuating said controls to stabilize the plane about its pitching and rolling axis, said means comprising electromagnets designed to exert a positive force for either direction of operation of said controls, an electrical circuit connecting said electromagnets to a source of electrical energy, and switches for automatically controlling said circuit to energize said electromagnets in response to pitching and rolling of said aeroplane, said switches comprising a column of mercury of inverted V-shape having the mercury electrically connected in said

circuit and being adapted to open said circuit in the manner specified.

8. In an aeroplane, automatic steering control comprising, a pair of electromagnets for actuating the rudder, an earth-inductor-compass-armature having a pair of brushes connected to power amplifiers, a pair of relays controlling the flow of current to said electromagnets and connected to be energized by said power amplifiers, said earth-inductor-compass-armature being responsive to deviations from a set course to energize said magnets and actuate the rudder controls.

9. In an aeroplane, the combination with elevator controls and aileron controls of automatic means for actuating said controls to stabilize the plane about its pitching and rolling axes, said means comprising electrical operating means adapted for exerting positive force for either direction of operation of said controls, an electrical circuit connecting said operating means to a source of electrical energy, and switches for automatically controlling said circuits to energize said operating means in response to pitching and rolling of said aeroplane, said switches comprising a column of mercury of inverted V-shape having the mercury electrically connected in said circuits, and being adapted to open said circuits in the manner specified.

In testimony whereof I have hereunto set my hand.

JOHN FOLINO.
